Primary Examiner — Clare E Heflin*(74) Attorney, Agent, or Firm* — QuickPatents; Kevin Prince(57) **CLAIM**

I claim the ornamental design for an exterior light cover, as shown and described.

DESCRIPTION

FIG. 1 is a perspective view of an exterior light cover, showing my new design;

FIG. 2 is a top plan view thereof, the bottom plan view being a mirror image thereof;

FIG. 3 is a left-side elevational view thereof, the right-side elevational view being a mirror image thereof;

FIG. 4 is a rear elevational view thereof; and,

FIG. 5 is a front elevational view thereof.

The broken lines showing a lightbulb in FIG. 1 and mounting apertures in FIG. 4 depict environmental matter and form no part of the claimed design.
